UNITED STATES PATENT OFFICE.

CHARLES L. SOCKWELL, OF NORTH WILKESBORO, NORTH CAROLINA, ASSIGNOR TO NEW WILLIAMS MILL COMPANY, INCORPORATED, OF NORTH WILKESBORO, NORTH CAROLINA.

WOOD-SAWING ATTACHMENT FOR TRACTORS.

Application filed March 24, 1923. Serial No. 627,364.

To all whom it may concern:

Be it known that I, CHARLES L. SOCKWELL, a citizen of the United States, residing at North Wilkesboro, in the county of Wilkes 5 and State of North Carolina, have invented a new and useful Wood-Sawing Attachment for Tractors, of which the following is a specification.

The object of my invention is to provide 10 an improved sawing attachment specially adapted for use on a Fordson tractor; to provide improved means for attaching the device to the tractor; to provide means for permitting of elevating the attachment when 15 desired; and to provide novel means for readily detaching and attaching the device with clamps to the radiator base of the tractor. It is an especial object of my invention to provide novel clamping means 20 adapted to be retained permanently on the tractor radiator base which will not interfere with the ordinary use of the tractor. It is also my object to provide a novel combination and arrangement of parts disclosed 25 in the accompanying drawings, in which:

Figure 1 is a side elevation of my invention;

Fig. 2 is a top plan of same;

Fig. 3 is an enlarged top plan, partly in 30 section, of member 2 in clamped position on the radiator base;

Fig. 4 is a detail perspective view of member 2, detached and inverted;

Fig. 5 is an enlarged top plan of member 3 in clamped position on the radiator base; and

Fig. 6 is an enlarged perspective view of member 3 in inverted position detached from the radiator base.

Like numerals indicate like parts in each 40 of the several views.

Referring to the accompanying drawings, the radiator supporting base is designated 1. I provide a left hand clamp 2 (viewed 45 from the point of observation of the occupant of the tractor) suitably shaped to engage around the adjacent edge of the radiator base 1, as shown in Fig. 3; and I provide a right hand clamp 3, suitably 50 shaped to engage around the opposite portion of the right hand side of the radiator supporting base 1. Clamps 2 and 3 are mounted on a long bolt 4 which is provided with a round head 5 and a threaded end

8. Left hand clamp 2 is provided with suitable ribs 17, said ribs terminating in curved outer surfaces 18 which engage the radiator base 1, the said ribs being mounted on the clamp base 16 which has a cylindrical extension 30, the clamp 2 having a channel 31 extending through said extension 30 and through which the said bolt 4 is inserted, as shown in Fig. 3. The left-hand wooden arm 19 of the saw attachment frame has a cylindrical opening 32 to loosely receive the cylindrical extension 30 of clamp 2. I provide a washer 7 engaging over the head 5 of bolt 4 and securing the wooden arm 19 in its normal position on extension 30 of clamp 2, the washer 7 being releasably fastened on the head 5 by cotterpin 6. On the opposite side of the radiator base the clamp 3 consists of a base 14 provided with a segment of a cylinder 11 which has curved recessed portions 12 to engage the pipe portion of the radiator base 1, as shown in Fig. 5. The base of the clamp also has a recessed portion 15 and is provided with a central opening 13 through which the threaded end of the bolt 4 is inserted. The outer portion of the base 14 of member 3 also is provided with a recessed portion 33 to receive the inside nut 9, as shown in Fig. 5. The wood saw attachment has a left hand metal arm 20 which engages over the threaded end 18 of long bolt 4 and is adjacent to the base 14 of right hand clamp 3 and is detachably held in place by nut 10, as illustrated in Fig. 5. I provide a short wooden arm 21 attached to the metal arm 20 and to which in turn the inclined uprights 22 is secured. Mounted on the inclined uprights 22 is the circular saw shaft 24, carrying a circular saw 25. I also provide a guide frame 28 for supporting the blocks of wood in place 95 while the sawing is proceeding. Shaft 24 carries a pulley 26 over which runs the belt 27 which is driven from the belt pulley of the belt pulley attachment on Fordson tractors, which attachment is used for driving other machinery when the tractor is stationary.

The saw frame arms 19 and 20 may of course be of any suitable material, that illustrated and described being however my 105 preferred construction. I may also provide any suitable means for detachably securing the ends of arms 19 and 20 on the bolt 4,

the means illustrated and described however being my preferred construction. I may also suitably shape clamps 2 and 3 for use with any desired tractor.

5 In applying the device, the attaching clamps 2 and 3 are applied to the tractor radiator base and the bolt 4 is then inserted through them and the clamps are secured on the tractor base where they need not be further disturbed. In other words, these 10 clamps remain on the tractor, whether the saw is used or not, after the clamps are once attached as they need not in any way interfere with operations of the tractor in other 15 duties to which it may be put when not engaged to the saw. To attach the saw frame, the wooden arm 19 of the saw frame is inserted over the head 5 of bolt 4 and over cylindrical extension 30 of clamp 2, and then 20 fastened in its operative position by inserting the cotter pin 6 through the bolt head 5. The saw is then moved a little to the left and the steel arm 20 is sprung outwardly slightly so that the bolt 4 will go through the hole in 25 the arm 20. The nut 10 is then applied to hold the arm from working loose from the nut of bolt 4. The saw is now ready for belting to the driving pulley of the tractor, and when the belt is in position, the attachment 30 is ready for use for sawing. The bolt 4 serves as an axis on which the tractor arms 19 and 20 may pivot to permit of swinging the entire saw frame to a raised position. This is done without requiring any loosening 35 of the nut 10 on the end of the bolt 4. The attachment is at all times readily clamped to the radiator base, by means of

screwing up the nut 9, as shown in Fig. 5, which is positioned in the cutaway portion 33 of clamp 3 and out of contact with the 40 arm 20, which is pivotally mounted on the end of bolt 4. The saw arms are not bound tightly on the bolt but are easily moved to raise the saw frame.

What I claim is:

1. In a device of the class described, opposed clamps suitably shaped to engage opposite portions of the radiator supporting base, one of said clamps having an exterior cutaway portion, a bolt extending through 50 said clamps, a nut engaging on the threaded end of the bolt and seating in the cutaway portion of the clamp to permanently secure the clamps on the radiator support base, and a wood sawing attachment having extended 55 arms swingably mounted on the clamping bolt, and means for detachably and loosely securing said arms on the opposite ends of the bolt whereby the arms carrying the wood sawing attachment may be swung to elevated 60 position without loosening the clamps which engage opposite portions of the radiator supporting base.

2. As a new article of manufacture for use 65 as a clamping device for a wood sawing attachment, the combination of a clamp base, an upstanding segment of a cylinder formed integral with said base, said segment having slotted portions to permit the edge portions 70 of the segment to engage the radiator base, the clamping base having a cutaway portion to receive a nut.

CHARLES L. SOCKWELL.
